(57) **CLAIM**

The ornamental design for an aiming device for improving golf putting and chipping, as shown and described.

DESCRIPTION

FIG. 1 is a top view of my aiming device for improving golf putting and chipping.

FIG. 2 is a bottom view thereof.

FIG. 3 is a front elevational view thereof.

FIG. 4 is a rear elevational view thereof.

FIG. 5 is a side elevational view thereof.

FIG. 6 is a perspective view thereof.

FIG. 7 is a top view of a second embodiment of the aiming device for improving golf putting and chipping as disclosed in FIG. 1;

FIG. 8 is a bottom view thereof;

FIG. 9 is a front elevational view thereof;

FIG. 10 is a rear elevational view thereof;

FIG. 11 is a side elevational view thereof; and,

FIG. 12 is a perspective view thereof.

The hatching pattern disclosed in FIGS. 7-12 represents a different color.
